UNITED STATES PATENT OFFICE.

ALFRED BERESFORD HAWES AND JOHN WHEELER, OF LONDON, ENGLAND.

SAFETY-CATCH FOR HAND-BAGS, ATTACHE-CASES, AND THE LIKE.

1,163,534.

Specification of Letters Patent.

Patented Dec. 7, 1915.

Application filed June 26, 1914. Serial No. 847,484.

To all whom it may concern:

Be it known that we, ALFRED BERESFORD HAWES and JOHN WHEELER, subjects of the King of Great Britain, and both residents 5 of London, England, have invented certain new and useful Improvements in Safety-Catches for Hand-Bags, Attaché-Cases, and the like, of which the following is a specification.

10 This invention relates to an improved safety catch for handbags, attaché cases and the like.

It consists in an auxiliary fastening adapted automatically to coöperate with the 15 handle fittings of the bag to prevent the same from opening should it be inadvertently taken up by the handle without being previously secured by means of the ordinary fastenings.

20 In the accompanying drawings we have illustrated a practical embodiment of our invention which is shown applied to an attaché case.

Figure 1 is an elevational view of part of 25 an attaché case showing a double hook fitting slidably attached to the closing flap of the case and adapted to engage the handle ring as will hereinafter be described. Fig. 2 is a plan view projected from Fig. 1.

30 Referring to these drawings, the numeral 1 designates the body of an attaché case of which the lid or cover 2 is provided with the usual closing flap 3. The handle 4 of the case is attached to rings 5 pivoted in fittings 6 in the usual manner. In the arrangement shown in Figs. 1 and 2 the safety catch 7 is slidably mounted on a base plate 8 which is riveted to the closing flap 3 by means of the shouldered rivets 9. These rivets are 35 secured to the plate before it is attached to the closing flap and are passed through suitable holes in the said flap and riveted over washers 10. The catch member 7 is provided with two hooks 11 and also with slots 40 12 whereby it is rendered slidable upon the pins 13. These pins are riveted to the base plate 8 and provided with heads 14 by means of which the catch member 7 is prevented from leaving them.

45 The operation of the device is as follows: When the case is set down the handle ring 5 naturally falls to a position below the plane of the catch fitting, as shown in the

drawings, but the action of taking up the case by the handle raises the ring to an 55 approximately vertical position thereby causing it to engage one of the hooks 11. Which hook it actually engages will be determined by the direction in which it happens to lie before the case is taken up. It 60 will be seen however that whichever hook is engaged the sliding connection between the catch member 7 and the base plate 8 permits the handle ring to rise to the full extent without straining the closing flap 3. 65 The length of the slots 12 limits the motion of the catch member.

What we claim and desire to secure by Letters Patent is:

1. A safety catch for handbags, attaché 70 cases and the like, said catch comprising a double hook member, slidably mounted upon the closing flap of the bag and projecting into the path of the handle ring, said catch being adapted when in one position to hold 75 the bag closed, the arrangement being such that the catch slides in a plane above that normally occupied by the handle ring when the bag or the like is set down but, when said bag or the like is taken up by the handle, the handle ring comes into engagement with one or other of the hooks of the said 80 catch and, while still remaining in engagement with it, slides it into such a position that the closing flap is not strained. 85

2. A safety catch slidably attached to the closing flap or equivalent portion of a handbag or the like and adapted automatically to engage a handle ring when said bag or the like is taken up by the handle, said 90 safety catch fitting comprising a plate riveted to the closing flap or equivalent and a double hooked member provided with a slot which coöperates with a suitable pin upon the plate aforesaid to attach said double 95 hooked member to said plate while permitting it to slide relatively thereto within suitable limits.

In testimony whereof we affix our signatures in presence of two witnesses.

ALFRED BERESFORD HAWES.
JOHN WHEELER.
